Attorney

UNITED STATES PATENT OFFICE.

JOSEPH V. KOERPERICH AND LEO J. HAUSER, OF EPWORTH, IOWA.

FEED BOX FOR STOCK.

Application filed June 4, 1924. Serial No. 717,759.

To all whom it may concern:

Be it known that we, JOSEPH V. KOERPERICH and LEO J. HAUSER, citizens of the United States, residing at Epworth, in the 5 county of Dubuque and State of Iowa, have invented certain new and useful Improvements in a Feed Box for Stock, of which the following is a specification.

This invention relates to an improved 10 food box for cattle, and the like, which is primarily intended to contain salt.

In conceiving and producing this invention, we have perfected one, which is exceedingly desirable for outdoor use, due to 15 the fact that it is of the animal controlled or actuated type, thus obviating the presence of an attendant, yet permitting the stock to be well supplied with salt, at their leisure.

20 In carrying out the invention, it has been our primary aim, to utilize a structure which is practical, automatic in operation, capable of operating with precision, and one in which the contents of the box are at 25 all times well preserved, against accidental displacement, or destruction from the weather.

An important factor of the invention is 30 the automatically operable gravity closed cover for the box, which is entirely animal actuated, and limited in its opening movement, to prevent it from going beyond dead center to insure prompt closing as soon as 35 the actuating means is rendered ineffective by the animal.

Other features and advantages of the invention will become apparent from the following description and drawings.

In the accompanying drawing, forming a 40 part of the application, and in which like numerals are employed to designate like parts throughout the same:

Figure 1 represents a side elevation of a 45 feed box constructed in accordance with this invention.

Figure 2 is a front elevation thereof.

Figure 3 is a top plan view.

Figure 4 is a detail section, showing more 50 clearly the pivotal connection of the cover.

55 In carrying out the invention, we use a substantially rectangular frame, which is formed from a plurality of comparatively short angle irons 1; the horizontal flanges of which are directed inwardly. A skeleton structure is completed through the use

of a plurality of vertically disposed angle irons 2, the forward pair of which is comparatively short, while the rear ones of which are of a greater height. The aforesaid frame is connected to the angle irons 2, 60 at a point between the ends of the latter and the portions of the irons 2 below this frame, constitute anchoring legs, by means of which the device is securely anchored in the ground. Fitted into the frame work 65 of angle iron is a galvanized iron box 3, the upper ends of which is open, and inclined downwardly from the rear legs to the tops of the front ones. A cover 4 completely closes this open end of the box and 70 is pivotally connected, as at 5, (see Figure 4) thereto. If desired, strap hinges 6 may be used for this purpose. It is to be observed that the upper end of the cover extends well beyond the rear wall of the box, 75 and is provided with an extended flange 7, to effectively shed water. Of course, the longitudinal edges of the cover are down-turned to provide flanges, and it is obvious that with this arrangement, a substantially 80 water proof container is had. As before intimated, the cover 4 is automatically elevated by animal actuated means. While this means could be constructed otherwise, it preferably comprises a platform 8, which 85 is secured to the extend ends of a pair of levers 9, these levers being pivotally connected to the front legs of the box, as at 10 and 11, to permit tilting of the platform. Guides 12 are secured to the rear 90 legs of the structure, and the corresponding ends of the levers operate therein, the upward movement of the levers being limited by these guides. The rear ends of levers 9 are active on a pair of vertically disposed push rods 13, which are pivotally connected at their lower ends thereto, and it is the rods 13 that serve to raise the cover 4. To accomplish this, a cross piece 14 is rigidly fastened to the upper side of 100 the cover, just downward of the pivot for the latter, and the ends of this cross piece are reduced and extended through elongated slots 15, in the push rod. When the parts are in normal positions, the reduced ends 105 seat in the lower ends of the slots. These reduced ends may be threaded and retaining nuts may be fitted on them. As observed, the parts 9 and 13 are duplicated on opposite sides of the box to insure precision 110

in the operation of the parts. It is highly desirable to limit the upward swing of the cover and to accomplish this, we utilize a pair of wire slides 16, which are connected 5 at their upper ends to the cross piece 14 and have their lower ends looped and sliding through combined guide and stop eyes 17, on the sides of the box. It is yet to be pointed out that counter balanced weights 10 18, are carried by the push rods to insure proper return of the platform to its normal position.

In practice, the salt filled box is placed at a convenient point in the field, and the 15 supporting legs of the structure are driven well down into the ground, to prevent the same from being capsized by the animal. As a bait, a small quantity of salt is placed 20 on top of the platform and since stock has a keen sense of smell for this kind of food, they will be attracted to the box. Of course, after the animals become accustomed to using the device, it is even unnecessary to use this bait. The animal in seeking 25 more salt will step upon the platform, and in so doing will depress the same to an extent to exert an upward stress on the push rod, which, as is evident will swing the cover to open position. As before stated, 30 this cover is limitaneously movable and cannot pass beyond dead center. Hence, as soon as the platform is relieved of the animal's weight, the cover will close by gravity. Attention is directed to the fact that

the elongated slots in the upper ends of the 35 push rods permit the cover to have a small amount of play, which is really essential in a device of this class, to eliminate breakage by the bobbing and upward thrust of the animal's head against the cover. It is 40 to be observed, too, that by properly counter-balancing the platform, the latter will swing to its normal position, despite the fact that it may be weighted slightly with 45 accumulated mud.

Undoubtedly the foregoing description and drawings, will suffice to present a clear comprehension of the invention. Therefore, it is thought unnecessary to enter a 50 more detailed description.

We claim:

An animal controlled feed box comprising an open top box, an inclined gravity lowered cover for said box pivotally connected to the latter at one end, a pivotally mounted animal depressed platform, vertically disposed push rods, pivotal connections between said push rods and platform, sliding connections between the upper ends of said push rods and said cover, depending slides connected with said sliding connections, and combined stop and guide eyes through which said slides pass.

In testimony whereof we affix our signatures.

JOSEPH V. KOERPERICH.
LEO J. HAUSER.
